UNITED STATES PATENT OFFICE.

SVANTE ADOLF PETTERSON, OF EUREKA, KANSAS.

TONGUE-SUPPORT.

1,049,597.

Specification of Letters Patent.

Patented Jan. 7, 1913.

Application filed June 21, 1911. Serial No. 634,483.

To all whom it may concern:

Be it known that I, SVANTE ADOLF PETTERSON, citizen of the United States, residing at Eureka, in county of Greenwood and State of Kansas, have invented certain new and useful Improvements in Tongue-Supports, of which the following is a specification.

My invention relates to an improvement in tongue supports, and more particularly for the tongue or pole of mowing machines, or heavy vehicles.

The invention consists in certain novel features of construction and combinations of parts which will be hereinafter fully described and pointed out in the claims.

In the accompanying drawings, Figure 1 is a view in elevation showing the invention applied to a tongue or pole; and Fig. 2 is a detail vertical sectional view through the support on the line 2—2 of Fig. 1.

A, represents the pole or tongue, and B, is the supporting bar, which bar is provided with a head 1 which is pivotally mounted between the plates 2, 2, connected to the sides of the bar. The lower surface of the head is rounded, as at 3, at one edge, and is made flat or square at the opposite edge, as at 4, whereby the bar is capable of swinging laterally in one direction only with respect to the head, as the squared shoulder or portion 4 causes the bar to be normally held rigid in a vertical position. A clamp 5 is pivotally connected to the head 1 and extends over and around the pole A and is fastened thereto by a screw bolt 6. A bolt 7 connects the clamp 5 to the head 1, and connected to the bolt is a coil spring 8, which in turn is connected to the bar B for causing the bar to return to its normal or upright position when swung laterally upon the head 1. A coil spring 9 is connected to the pole or tongue A, and to the bar B for normally holding the bar in a vertical position and for returning it to its vertical position when swung rearwardly.

The object of the bar is to form a means of support for the tongue when the machine

or vehicle is at rest, to relieve the weight from the draft animals. In harvesters, 50 mowing machines and the like, a great deal of the weight of the machine is thrown upon the horses or draft animals, and it is to overcome this difficulty that I have provided the pivoted bar or support. The support has free movement with respect to the tongue, so that in case of its coming in contact with an obstruction, it can be swung rearwardly against the tension of the spring 9, but after passing over the obstruction it 60 will be drawn back to its normal or vertical position, due to the tension of the spring 9. In instances where the support would strike obstructions, which would cause it to swing laterally, the spring 8 would be 65 placed under greater tension, and after the obstruction had been passed, the spring would draw the bar or support to its normal position against the shoulder 4.

Having fully described my invention, 70 what I claim as new and desire to secure by Letters Patent, is:—

1. The combination with a pole, of a support having a head pivotally connected thereto, means pivotally connecting the head 75 to the pole whereby the support is capable of movement in a longitudinal and lateral direction, and means on the head for limiting the movement of the support in one of its movements. 80

2. The combination with a pole, of a support having a head pivotally connected thereto, means pivotally connecting the head to the pole whereby the support is capable of movement in a longitudinal and lateral direction, means on the head for limiting the movement of the support in one of its movements, and means for causing the support to return to its normal position. 85

In testimony whereof I affix my signature, 90 in the presence of two witnesses.

SVANTE ADOLF PETTERSON.
